UNITED STATES PATENT OFFICE

102,891

DESIGN FOR A HEBREW ALPHABET

Samu-El Ish-Shalom, New York, N. Y., assignor
to Mergenthaler Linotype Company, Brooklyn,
N. Y., a corporation of New York

Application November 13, 1936, Serial No. 65,882

Term of patent 14 years

To all whom it may concern:

Be it known that I, Samu-El Ish-Shalom, a citizen of the United States, residing in the city of New York, in the State of New York, have invented a new, original, and ornamental Design for a Hebrew Alphabet, of which the following is a specification, reference being had to the accompanying drawing forming a part thereof. The figure of the drawing is a face view of the Hebrew alphabet showing my design.

The new ornamental font of the Hebrew alphabet is characterized by the formation of various letters with a heavy shading based on a modern letter design with the letters uniformly proportioned as shown.

I claim:

The ornamental design for a Hebrew alphabet substantially as shown and described.

SAMU-EL ISH-SHALOM.
